[57] ABSTRACT

A horizontal elongated bar is secured by outwardly extending brackets to the top outside surface of the tail gate of a pick up truck.

FIG. 1

FIG. 2

FIG. 3

INVENTOR.
L. B. LANE

TAIL GATE PROTECTOR AND LOAD BAR

SUMMARY OF THE INVENTION

I have invented a new type of tie bar structure which can horizontally span the rear of the body of a pick up truck but can be vertically shifted in position in accordance with the position of the tail gate. To this end, I provide brackets which extend horizontally rearward of the tail gate when the gate is in vertical position. These brackets are rigidly secured to opposite sides of the gate adjacent the top edge thereof. An elongated bar extends horizontally between the brackets parallel to the tail gate and is supported at each end by the corresponding bracket.

In a truck, my invention has a variety of uses such as a tie down bar, a lift bar or a load assist bar.

BRIEF DESCRIPTION OF THE DRAWINGS

In the drawings:

FIG. 1 is a perspective view of my invention in use;

FIG. 2 is a side view thereof; and

FIG. 3 is a detail exploded view of certain parts used in my invention.

DETAILED DESCRIPTION OF PREFERRED EMBODIMENTS

Referring now to FIGS. 1-3, a pick up truck has a body 10 with a tail gate 12 that can be raised to a vertical position or lowered to a horizontal position. Each side of the gate adjacent the top edge 14 has a horizontal threaded bore 16. A separate bolt 18 threadedly en-

gages the bore. Each of two separate brackets 20 is adapted to extend outward from the outer surface of the gate at right angles thereto and has an opening 22 in one end through which the bolt passes to hold the bracket in place. Both brackets lie in parallel vertical planes. Each bracket carries at the other end a horizontal sleeve 24, the two sleeves being aligned and facing each other. A horizontal bar 26 extends between the brackets, each bar end being held within and supported by a corresponding sleeve.

While I have described my invention with particular reference to the drawings, such is not to be considered as limiting its actual scope.

What is claimed is:

1. In combination with a tail gate which can be swung between vertical and horizontal positions:

20 bracket means secured to opposite sides of the gate adjacent the top edge thereof and extending outward from the outer surface of the gate at right angles thereto; and
a horizontal bar extending between and supported by said bracket means.

2. The combination as set forth in claim 1 wherein said means lie in parallel vertical planes.

3. The combination as set forth in claim 2 wherein each bracket has a horizontal sleeve in which a corresponding end of the bar is detachably disposed.

30 4. The combination as set forth in claim 3 wherein the sleeves are disposed along a common horizontal line.
